B. A. MUELLER,
AIR MOISTENER FOR HOT AIR FURNACES,
APPLICATION FILED AUG. 23, 1919. RENEWED MAY 26, 1921.
1,384,331. Patented July 12, 1921.

Inventor:
B. A. Mueller
Geo. R. Evans
Atty.

UNITED STATES PATENT OFFICE.

BERNHARD A. MUELLER, OF EAST ST. LOUIS, ILLINOIS.

AIR-MOISTENER FOR HOT-AIR FURNACES.

1,384,331.

Specification of Letters Patent. Patented July 12, 1921.

Application filed August 23, 1919, Serial No. 319,425. Renewed May 26, 1921. Serial No. 472,886.

To all whom it may concern:

Be it known that I, BERNHARD A. MUELLER, a citizen of the United States, residing at East St. Louis, in the county of St. Clair and State of Illinois, have invented certain new and useful Improvements in Air-Moisteners for Hot-Air Furnaces, of which the following is a specification.

My invention relates to air moisteners for hot air furnaces.

The object of the invention is to provide a readily attachable air moistener for hot air furnaces in which the supply of water to the hot air chamber at the top of the furnace casing will be automatically controlled by a controller actuated by changes in condition of the air in the casing. A further object is to provide a controller in the form of a sectional bar built of sections of wood secured together crosswise of the grain.

These objects I accomplish by the construction shown in the accompanying drawing, in which:

Figure 1 is a perspective partly in section of a hot air furnace with my improved air moistener applied.

Fig. 2 is an enlarged detail perspective, and

Fig. 3 is a sectional plan view of the valve.

The furnace is provided with the usual outer casing 1, at the top of which is the hot air chamber 2.

The casing 1 is provided just below the hot air chamber 2 with an opening 3 formed by punching in a tongue 4 which inclines inwardly and upwardly and a similarly formed opening 5 is formed some distance below the opening 3, the tongue 6 of which inclines downwardly and inwardly, as clearly shown in Fig. 2. These two openings 3 and 5 are connected by a flue in the form of a tube 7 open at one side and there provided with attaching flanges 8' riveted or otherwise secured to the furnace casing. The top and bottom ends of the tube 7 are closed, as shown at 8 and 9, so that the hot air between the casing and fire box will be directed by the lower tongue 6 into the tube or flue 7, and when it reaches the upper opening it will be directed by the upper tongue 4 into the hot air chamber 2. This arrangement causes a draft of hot air through the tube.

Within the flue or tube 7 there is placed a longitudinally expandible and contractible bar 10, shown in the present instance as

formed of blocks of wood 11, arranged crosswise of the grain. These blocks of wood 11 are of cross grained wood with the grain of one block crosswise of the other to prevent warping of the bar and the blocks are secured together in any desired manner, as by staples 12.

The bar 10 thus formed is secured at its lower end to the bottom of tube 7, and at its upper end is provided with a stiff rod 13 which extends up through an aperture 14 in the closed upper end of said tube 7. The rod 13 is adjustable in length by means of a turnbuckle 14'.

The upper end of the rod 13 is connected to one end of a horizontal threaded arm 15 secured between its ends to the threaded stem 16 of a needle valve 17 mounted in the valve casing 18. This connection is made by means of a short chain 19 extending from the rod 13 to a nut 20 mounted adjustably on threaded arm 15 so that by adjusting the nut the arm 15 may be made to open the valve to the desired extent. The opposite end of the arm 15 is provided with an adjustable weight 21 also threaded on arm 15 and adapted to close the valve. A very nice adjustment of the valve is thus provided. The valve casing 18 is connected with the water supply in any desired manner. As shown in the drawing, the valve casing is connected by a pipe 25 with the hot water pipe 26 leading from a coil, not shown, in the furnace fire box to a domestic boiler, also not shown, but well known.

The valve casing 18 is further provided with a discharge nipple 27 at one side under which is placed a trough 29 extending thence through an aperture 30 in the hot air chamber, where it discharges preferably into an open pan or tray 31.

It will be seen that a draft of hot air will pass upwardly through flue or tube 7 and when the air is too dry the hygrometric bar 10 will contract longitudinally and so pull down on rod 13, which in turn will rotate needle valve against the action of its closing element and so permit water to discharge into the trough 29. As soon as the condition of the air changes by reason of added moisture the bar 7 will expand and so allow the needle valve to be closed by its weight. Any form of valve may be employed, however, capable of being opened and closed by the bar. It is manifest that the tube 7 may be placed on the inner side of the furnace

casing, if so desired, and that other forms of atmospherically contractible and expansible rods or bars may be employed.

What I claim is:

- 5 1. An air moistener for hot air furnaces comprising a tube adapted to be secured to a furnace casing and form a hot air flue, an atmospherically contractible and expansible rod located in said tube, and provided with 10 a valve actuating rod at its upper end, a valve actuated by said rod, and means for conducting the water discharged from the valve into the hot air chamber of a furnace.
- 15 2. The combination with a hot air furnace having upper and lower openings in one side, of a tube or flue secured to the side of the casing and communicating at its upper and lower portions with said openings, an atmospherically controlled bar within said 20 tube or flue and secured at its lower end to the bottom of the flue, a rod extending from the bar through the top of the flue or tube, a water supply valve to which the upper end of the rod is connected, and a trough leading 25 from the discharge side of the valve into the hot air chamber.
- 30 3. The combination with a hot air furnace provided with upper and lower openings in its casing, a downwardly and inwardly inclined tongue at the upper edge of the lower opening, and an upwardly and inwardly inclined tongue at the lower edge of the upper opening, of a tube closed at its ends, secured to the outer side of the casing and communicating with said two casing openings, an atmospherically controlled, longitudinally contractible and expansible bar secured at its lower end within the tube and provided with 35 a rod extending through the closed upper end of said tube, and a water supply valve controlled by said bar and rod and discharging into the hot air chamber of the furnace.
- 40 4. The combination with a hot air furnace provided with upper and lower openings in the side of the casing, a tube closed at its ends and communicating with said openings, an atmospherically controlled bar formed of a series of cross grained wooden blocks secured together to form a rigid compound element and fixedly secured at its lower end to the bottom of the tube, a water supply valve operatively connected to the upper end of said bar and discharging into the hot air chamber of the furnace.
- 45 5. The combination with a hot air furnace, of a tube secured to the furnace casing and communicating at its upper and lower ends with the interior thereof to form a hot air flue, an atmospherically controlled contractible and expansible bar secured at its lower end within the tube or flue and provided at its upper end with a rod extending through the upper end of said tube, a water supply valve provided with an offtake leading into the hot air furnace and having an 50 actuating arm, and means for adjustably connecting the upper end of the rod with said operating arm.
- 55 6. An air moistening attachment for hot air furnaces comprising a tube adapted for attachment to a furnace casing to form a hot air flue, an atmospherically controlled bar secured at its lower end within the tube or flue and having a valve operating rod extending through the upper end thereof, a 60 water supply needle valve for the hot air chamber provided with a horizontal threaded arm, an adjustable nut on one end of the arm to which the upper end of said rod is connected, and a weight adjustable on the 65 other end of said threaded valve arm.

In testimony whereof I affix my signature.

BERNHARD A. MUELLER.
